FABRIC MAKING

Raymond J. Southwell, New Rochelle, and Theodore H. Wickwire, Jr., New York, N. Y., assignors to Welded Fabrics Corporation, New York, N. Y., a Corporation of New York

Application November 14, 1930
Serial No. 495,598

10 Claims. (Cl. 140—112)

Our invention relates to making mesh fabric. The invention is herein described with special reference to manufacture of electrically welded wire fabric, but its advantages can be realized 5 with strands of other material, and fastened together in other ways.

Such fabric has neither warp nor woof in the ordinary sense, but can be made in continuous strip form from a set of continuous parallel 10 wires or strands laid or folded recurrently inwardly from edge to edge of the strip width at a common angle to the longitudinal direction thereof, and with each fold or lay over a part of the preceding fold or lay, so that the leading 15 wire of the set is always at one face of the fabric and the rearmost wire of the set is always on the other face, with the intermediate wires of the set in each lay or fold disposed partly at one face and partly at the other in graduated relation 20 therebetween.

Such a fabric has the advantage from the standpoint of manufacture that it can be formed from multiple wires rapidly and continuously by our invention, and that preliminary preparatory 25 operations, such as winding warp on a warp roller, tying on new warps, and the like, are eliminated.

The principal object of the invention consists 30 in the process for making such fabric.

Additional objects include making provision 35 for forming and holding the mesh while moving along on conveyors; for continuous electrical welding of the mesh without derangement of the strands; for stretching the mesh into straight line relation at the time of welding; and for imparting a predetermined spacing at the welding point.

Other objects are in part pointed out below 40 and others are obvious from the description.

In the drawings:

Figure 1 is a general plan view;

Fig. 2 is a general side elevational view;

Fig. 3 is an end elevational view;

Fig. 4 is an enlarged plan view of the mechanism 45 for effecting transverse reciprocation of the wire supplying nozzles;

Fig. 5 is a section on line 5—5 of Fig. 4;

Fig. 6 is a bottom plan view, with parts broken 50 away, of the structure shown in Fig. 5;

Fig. 7 is a section taken substantially on line 7—7 of Fig. 5;

Fig. 8 is a cross-section on line 8—8 of Fig. 5;

Fig. 9 is a cross-section on line 9—9 of Fig. 5;

Fig. 10 is a further enlarged front elevational 55 detail view of a portion of Fig. 4;

Fig. 11 is a diagrammatic perspective view of a mechanism for oscillating the wire supplying nozzles;

Fig. 12 is a detail section on line 12—12 of Fig. 1; 60

Fig. 13 is a front elevation, with parts broken away, of the apparatus shown in Fig. 12;

Fig. 14 is an enlarged plan view, partly in section, of a part of one of the conveyors taken at a region of conveyor divergence provided to 65 pull the fabric strands out straight preparatory to welding;

Fig. 15 is an enlarged sectional view of the welding mechanism taken on line 15—15 of Fig. 1; 70

Fig. 16 is a plan view of the showing of Fig. 15;

Fig. 17, 18, and 19 are diagrammatic views showing successive stages in the formation of the fabric; and 75

Figs. 20, 21, 22, and 23 are diagrammatic views illustrating successive stages in the movement of the wire supplying nozzles out past the wire holding members on one side and back on the other side thereof. 80

Reference character 10 designates two elongated continuously travelling parallel series of wire engaging, holding and releasing members, preferably formed—if the fabric is made to lie horizontally, as is ordinarily the case—as vertically extending pins which may be slightly hooked on their backs at 12 in order to prevent accidental disengagement of the wire therefrom, and also to insure a slight-downward sliding movement of the wire engaged thereby, in order 85 to permit the wire delivering nozzles 14 to clear same on the return stroke.

Various means may be used for producing the continuous forward movement of the wire engaging members 10 in the direction of arrow 16 90 on Fig. 1. That here shown consists of a pair of elongated parallel sprocket chains 18 running over and driven from sprockets 20, 20', fixed to opposite ends of cross shafts 21, 21', so as to move in unison. Such arrangement is not claimed herein as applied in the manufacture of fabric comprising warp and woof wires, same being a sole invention of applicant Southwell, and covered by his application Serial No. 436,949, 95 filed March 19th, 1930.

The connection of the members 10 to the links 22 of the sprocket chains 18 is such as to permit the members 10 on the conveyor chains to approach towards and recede from each other to some extent in order to increase or diminish 100 110

the tautness and straightness with which the wire is held, for releasing the fabricated product, etc., and also the arrangement is such as to relieve the sprocket chain 18 and sprockets 5 20 from side strain. These conditions are met in the form shown by securing the members 10 to slides 24 slidable in and out transversely to the direction of chain travel, in dove-tail-grooved slideway members 26, attached to chain 10 links 22, and the lateral strain imposed on the members 10 and slides 24 is taken by track rails 28 engaged by anti-friction rollers 30 on slides 24. A trackway 32 for rollers 30 may be provided between rail 28 and a parallel back rail 15 34, and the upper reaches 35 of the roller chains 18, whereon the mesh is formed run upon the horizontal tracks 38. A suitable machine frame work 39 is provided at each side of the relatively elongated machine to support rails 28 and 34, 20 tracks 38, and other machine parts.

In the making of welded wire fabric, the wire strands 40 are supplied, preferably from individual spools (not shown), and are run through a tensioning and positioning guide or guides 42, 25 whence they are distributed to the laying nozzles 14, which have a reciprocating movement transverse to the paths of members 10, 10, and operate to engage the wire strands 40 with pins or hooks 10 and to form a mesh built up and carried along 30 on the travelling pins 10 in a manner presently to be described; the strands are welded at 41; the members 10 are released from the welded fabric at 41^a; and the completed fabric is delivered to a take-up roll (not shown), or the like.

35 Referring now to the means for laying or folding wire strands 40 back and forth transversely, the wire receiving and distributing nozzles 14 are preferably arranged in a set extending parallel to the conveyors 18 and to stand substantially vertically, and the wire strands 40 are passed through the bores 46 therein, the mouths 48 of such bores 46 being preferably rounded and enlarged for the ready insertion and easy guiding of the wires, and the tips 50 at the lower end of 45 the nozzles through which the wire 40 is delivered, being pointed somewhat so as to facilitate the passing of the nozzles 14 between the hook members 10. Nozzles 14 are spaced the same distance apart as the members 10, and same are here shown 50 inserted and held in parallel holes in shaft 52, and shaft 52 is journaled near its two ends in bearings 54 on a cross-carriage 56 having a reciprocating movement transversely of the path of movement of sprockets 18 upon the guide rails 38.

55 With the form here shown, carriage 56 is actuated in its reciprocating movement by a revolving counterweighted crank 60 and connecting rod 62, and the timing of carriage 56 is controlled through bevel gears 64, 66, worm reduction drive 60 68 and crank 60 so that the carriage 56 moves across once in the same time interval that it takes for longitudinal advancement of half as many of the pins 10 as there are wire supplying nozzles 14.

When making use of crank arm actuation of 65 the cross-carriage 56, the speed of movement of the carriage is, of course, least at the ends of the stroke, and at such time, in order to accurately control the outward movement of the nozzles 14 past one side of the respective pins 10 and inwardly past the other side thereof, we impart an additional oscillating movement to the nozzles 14 and their carrying shaft 52, preferably deriving such movement from the rotational movement of crank 60 which is not subject to speed reduction, 70 as carriage 56 is.

For this purpose, the nozzles 14 are passed through a second shaft 70 parallel to shaft 52, and translatory movement is imparted to the member 70 to produce oscillatory movement of the nozzles 14 by means of a series of connecting rods 72, and 80 elbow levers 74, pivotally mounted on the cross carriage 56. The elbow levers 74 are operated in unison from a gang bar 76 to which longitudinal movement is imparted through connecting rod 78, crank 80, and shaft 82, said shaft 82 being actuated at each reversal of movement of the carriage 56 by means of the spinal projection 84 depending from said shaft 82 which moves in and out with carriage 56, being engaged by the upwardly projecting lug 86 rotating with the crank 60 and engaging said spinal projection 84 to turn shaft 82 somewhat and thereby produce outward pivotal movement of nozzles 14 at opposite ends of the travel of carriage 56.

85 For producing returning movement of the nozzles 14, we provide a pair of springs 88 and 90 which, by acting on crank arm 92 of shaft 82, serve respectively to bring the shaft 82 back to neutral position after being turned to either side therefrom, returning nozzles 14 to substantially 90 their normal position.

95 In order to avoid chattering movement of the nozzles 14, and any undue yielding thereof to the pull of the wires during the principal portions of the stroke of the cross carriage 56, we provide 100 locking means for holding the nozzles 14 in substantially vertical position during the entire movement of the cross carriage except at the periods of reversal, at which times they are unlocked to permit the additional oscillatory movement thereof above described.

105 The locking mechanism herein illustrated comprises coacting dog tooth members 94 and 96, one on gang bar 76, and the other upon the outer end of a slider 98 (Fig. 7) slidably mounted under carriage 56, and comprising said dog 96, slide rods 99 and 100, and a cross connecting cam member 102, said cam member 102 projecting downwardly from the carriage 56, and having a cam surface 104 adapted to be engaged by the cam 110 115 lower ring 106, concentric with the axis of the pivotal bearing 108 between the counterweighted crank arm 60 and its connecting rod 62. The clutch dog 96 on slider 98 is normally spring 120 pressed by a spring 110 into engagement with dog 94 on the gang bar 76, but immediately prior to reversals of the travel of the carriage 56, the clutch is released by the dog 96 being retracted by engagement, with cam 102, of the push ring 106 125 rotating with the crank 60, which said engagement is repeated at each 180° of rotation of said crank, whereupon the nozzles 14 are oscillated by the chain of elements actuated from the crank lug 86 and spring 88 or 90, as described.

130 The movement of nozzles 14, including movement with carriage 56, as well as the additional oscillatory nozzle movement imparted in the manner described, serves to carry the nozzles 14 and the wire strands 40 carried thereby outwardly past the pins 10 on one side thereof, and then 135 inwardly past the same pins 10 on the other side thereof, as indicated (for the nozzles and pins at one side of the apparatus) in Figs. 20 to 23, inclusive.

140 As indicated in said figures, the pins 10 move continuously towards the right. In Fig. 20, the dotted lines show the nozzles 14 moving outward to take the positions occupied by the pins 10, whereas the full lines indicate substantially the 145 relative positions upon a further outward move-

ment of the nozzles—and wires 40—and a further corresponding forward movement of pins 10. In the showing of Fig. 21, the nozzles 14 have moved outwardly past the leading side of the corresponding pins 10, while pins 10 have moved to the right, leaving intermediate spaces on the following sides of corresponding pins 10 through which the nozzles retreat. The nozzles 14 are shown in Fig. 22 moving backwardly and in the 10 act of passing the pins 10; and in Fig. 23, are shown to have moved beyond pins 10, all resulting in the wire strands 40, 40, having been guided, carried, hooked, or folded around pins 10. It will be understood that at the opposite end of the 15 carriage stroke the wire strands are engaged, in reverse manner from that shown in Figs. 20—23, with pins 10 at the opposite side or selvage of the mesh structure being formed.

As already noted, the pins 10 are preferably 20 undercut or hooked on their rear surfaces at 12, so that the strands 40 upon engaging therewith immediately slide down somewhat, leaving a clear path thereover for return passage of nozzles 14 and the laying of the successive bights of wire 40. 25 The production of the mesh in the manner described with its strands held in mesh relation on travelling pins 10 preparatory to being attached together, as by welding, is indicated in Figs. 17, 18, and 19.

30 Taking a ten nozzle machine and a 45° lay for simplicity of illustration, and numbering opposite pins alike in sets of 1 to 10, and 1' to 10', Fig. 17 shows the first lay or fold completed, the strands 40 engaging pins 1, 2, 3, 4, 5, 6, 7, 8, 9, and 35 10 at the start and on the other side engaging pins 6', 7', 8', 9', 10', 1, 2', 3', 4', and 5' respectively, this being due to forward travel of the pins that takes place during cross-travel of the nozzles. In Fig. 18, the progressive building 40 up of the mesh is illustrated at a point where the nozzles, in addition to having crossed over once, as in Fig. 17, have returned to the original side, the strands engaging the next set of pins 1 to 10, and in Fig. 18, the showing includes a 45 third crossing.

It will be seen that the successive lays or folds of the strands are rhombuslike in outline, divided along the shortest diagonal into two triangular parts, that nearest the laying nozzles forming always an underply,—to be later covered over by the wires of the succeeding lay or fold—and the remaining triangular part being superposed as a top layer or ply over the originally single ply part of the preceding fold. Thus the wire 50 fed from the nozzle 14 that is nearest the take up reel will always be found completely exposed on top of the mesh (if formed horizontally), that from nozzle 14 at the opposite end of the series 55 will always be found entirely on the under side of the mesh material, with a graduation therebetween through all the intermediate stages, the wire from the central nozzle, for example, being substantially half in the top ply and half in the under ply of the mesh. Such fabric and mesh 60 is not claimed herein, as stated above, being the sole invention of applicant Wickwire.

The mesh so laid and held in position by the travelling pins 10, but not as yet welded or otherwise fastened at the strand crossings, is indicated 65 by reference character 116. Preparatory to welding, or otherwise securing same, it is desirable that the wires be accurately positioned with respect to one another, and also straightened out. To do this, we may provide a roller 118 having a series 70 of rows of pins 120 of the spacing desired to be

secured in the production of the wire mesh, preferably arranged in the path of the mesh between the rows of pins 10 at a point immediately in advance of the welding apparatus so that the pins 120 enter between the wires and hold same 80 properly spaced apart during welding. It is ordinarily not necessary to drive the cylinder 118, except as same is driven by the engagement of the mesh with the pins 120 thereof, the cylinder or roller 118 being mounted to turn freely. This 85 takes care of the proper relative positioning of the wires at the point where they are to be welded, and the straightening or tautening of the wires preparatory to welding is secured by localized slight divergence of the track ways 32, 90 as at 122 (Fig. 14) and resulting localized increase of the distance between the pins 10.

In making welded wire mesh fabric, we provide means for securing the strands together at their crossings by welding, preferably by continuous electrical welding. In the arrangement shown, the wire mesh at the welding station 124 is moved with the travelling pins 10 over a ground roller 126, preferably of copper, and beneath a series of short welding rollers 134 having conducting ring portions 136, immediately above the wire crossings, with interposed insulation bands arranged flush with the roller surface to give a smooth roller surface so as not to distort the mesh. The number of conducting ring parts 136 and, therefore, or wire crossings to be welded by each of the welding rollers 134, is dependent on the capacity of the transformers used, rollers 134 100 illustrated having six welding ring surfaces and welding six crossings in groups of three each as 110 the mesh travels along. Multiple welds can be made simultaneously in this manner, care being taken to see that the roller section is sufficiently great to supply substantially equal current density for each weld. The distance between the 115 ground roller 126 and the upper welding rollers 134 is so adjusted and regulated that, whereas a single strand 40 can pass therebetween without completing the circuit, contact is made and the 120 circuit completed and weld made by two crossing wires passing between the rolls. Adjustable pressure applying means, such as weights 140, may be provided to apply pressure during welding proportioned to the gage of wire being welded.

It will be observed that with the carriage actuating mechanism arranged at one side of the travelers (right side in Fig. 3), the other side is left free and open and in making adjustments, as for example, for decreasing the width, the adjustment can be confined to the traveler on the 130 free side, leaving the other traveler undisturbed.

We may arrange to contact a spelter wire having a flux core, or equivalent, with the hot freshly welded wire junctures immediately after leaving the weld rolls, to produce local galvanizing 135 at the crossing points immediately after welding and thereby prevent progressive oxidation of the wire which has been subjected to oxidizing temperature during welding.

After welding, the fabric is complete and is released by the pins 10 being made to approach one another somewhat at 41° by a local slight approachment of the track ways 32, thereby permitting the pins to be withdrawn from the fabric as the chains 18 pass down over the delivery end 145 sprockets 20', whereupon the fabric may be delivered to a take-up roll, or otherwise disposed of, as may be desired.

While the diamond mesh herein shown has the 150 special form of squares with equal diagonals, it

will be understood that other forms can be made.

We claim:

1. The process of continuously making a strip of open mesh fabric which consists in arranging the several strands of a set of continuous strands to extend parallel to one another from edge to edge of the strip width, then parallel to one another thereover back to the first edge, and so on, while advancing same longitudinally of the strip 10 in crossing over or back a distance substantially equal to the width of the set of strands, whereby a substantially continuous and complete diamond-pattern mesh is obtained with substantially evenly spaced strand loops along the edges, 15 and securing the strands together locally at the points of crossing.

2. The process of claim 1, further characterized in that the strands are metallic and the fastenings at the points of crossing are produced by 20 electrical welding.

3. The process of making a continuous strip of open mesh fabric which consists in arranging the several strands of a set of continuous strands to extend parallel to one another from edge to 25 edge of the strip width, then parallel to one another thereover back to the first edge, and so on, while advancing same longitudinally of the strip in crossing over or back a distance substantially equal to the width of the set of strands, 30 whereby a substantially continuous and complete diamond-pattern mesh is obtained with substantially evenly spaced loops along the edges, holding the strands in the described relation by the marginal loops thereof and travelling same 35 longitudinally, and securing the strands together at their crossings while so held, and releasing and delivering the complete fabric continuously.

4. The process of claim 3, further characterized in that the strands are metallic, and the 40 fastenings at the points of crossing are produced by electrical welding.

5. The process of claim 3, further characterized in that the strands are of wire, and are secured together locally at crossings by electrical welding, and, preparatory to welding, the wires are straightened and their spacing substantially 45 evenly adjusted.

6. The process of producing a continuous strip of open mesh wire fabric which comprises leading the individual wires of a set or group of continuous wires across and back from edge to edge of the strip width, and at the same time longitudinally advancing same through such a distance 50

55

60

65

70

75

that the strand loops at the strip edges are substantially uniformly spaced, holding and travelling longitudinally the wires in such formation by engagement with the edge loops thereof, straightening the wires by imparting a lateral expansion to the wire formation while so held and travelling, welding the wires at their crossings in substantially a crossbelt or zone of their travel, and releasing the strand loops and delivering the completed fabric.

7. The process of making continuous open mesh fabric which comprises arranging a series of strands to recurrently cross one another in 80 layers of parallel strand portions and form a mesh in which the outside strands of the series are at opposite faces and the intermediate strands partly at each face, and securing the strands together 90 at their crossings.

8. The process of making a continuous strip of open mesh fabric which comprises folding a 95 set of parallel strands inwardly back and forth from and to the respective edges of the strip width while advancing same longitudinally of the strip, each fold being on top of a part of the preceding fold, and securing the strands together 100 locally at their crossings.

9. Continuous process of making mesh fabric comprising the steps of applying pull to a set of parallel wires by two sets of travelling pins spaced apart the width of the mesh while carrying the wires back and forth in a fixed path to engage marginal loops thereof with the pulling pins as they travel along, thereby forming a mesh of crossing wires in which the forward and rear wires of the set are on opposite sides and the 105 intermediate wires partly on one side and partly on the other in graduated fashion therebetween, and passing the travelling mesh so held between rollers included in an electrical circuit thereby welding the wires together at their crossings. 110

10. Process of continuous welding of wire mesh fabric which comprises passing wire mesh containing wires that cross one another in oblique relation continuously between elongated substantially cylindrical welding rolls spaced apart more 120 than one but not more than two wires thicknesses, and including such rollers in an electrical circuit, whereby crossed strands automatically complete the circuit and same are electrically welded together as they pass between the rolls. 125
